ORSWELL IGNITER COMPANY, OF BOSTON, MASSACHUSETTS, A
CORPORATION OF MAINE.

SPARKING PLUG FOR EXPLOSION-ENGINES.

No. 841,566.

Specification of Letters Patent.

Patented Jan. 15, 1907.

Application filed January 25, 1906. Serial No. 297,791.

To all whom it may concern:

Be it known that I, ISRAEL C. ORSWELL, a citizen of the United States, residing at Amesbury, in the county of Essex and State of Massachusetts, have invented an Improvement in Sparking Plugs for Explosion-Engines, of which the following description, in connection with the accompanying drawings, is a specification, like letters on the drawings representing like parts.

My invention relates to sparking devices for explosion-engines, and particularly to the construction of spark-plugs and induction-coils therefor.

My invention will be best understood by reference to the following description, when taken in connection with the accompanying illustration, of one specific embodiment thereof, while its scope will be more particularly pointed out in the appended claims.

In the drawings, Figure 1 is an elevation of a spark-plug embodying one form of my invention, and Fig. 2 shows in central vertical section the plug illustrated in Fig. 1.

Referring to the drawings and to the specific embodiment of my invention therein illustrated, I have shown a spark-plug for an explosion-engine provided with sparking terminals or electrodes combined in a single structure with an induction-coil, the secondary of which is in series with the sparking electrodes.

In the illustrated embodiment of my invention the coil comprises a suitably-proportioned primary winding *a*, which is wound upon the core *b*, the latter preferably consisting of a bundle of soft-iron wires with suitable insulating material interposed between the coil and core. Outside of the coil *a* and with the interposition of a layer of insulating material *c* is wound the secondary coil *d*, which, as usual, is of relatively fine wire. The coil thus constructed is incased within a covering *e* of suitable insulating material and placed within a cylindrical metallic casing *f*, which latter is lined with a thick removable sleeve *g*, of mica or other hard waterproof insulating substance.

The partially open end of the cylindrical casing at its rear end (upper end in Figs. 1 and 2) is closed by the mica or other insulating washer *h* and the pair of washers *i* and *j*, of like material, the latter being held between the end of the mica sleeve and the overturned walls of the casing end. Outside of the cas-

ing is the base-block of insulating material *o*, 55 upon which is mounted the apertured terminal lugs *p* *p'*, provided with suitable set-screws, to which the battery-leads may be readily connected. These lugs are held in position by screws threaded from the interior 60 of the casing and countersunk in the mica disk *i*. The lugs are suitably drilled to receive the primary coil-leads *q* *q'*, which are maintained in firm conducting contact with the lugs by means of tapered wedges *r* *r'*, 65 driven in from the outside, which wedges act also to close up the drilled hole against the entrance of moisture.

The opposite end of the casing is closed by the head *s*, having the threaded nipple *s'* 70 adapted to be screwed into a suitable aperture in the walls of the engine-cylinder in the usual manner. The casing-head rests against an annular mica ring *t*, which in turn lies against the thick porcelain insulating plate *u*, 75 the latter having a forwardly-projecting central portion *t'*, which fits into a corresponding recess in the head *s*.

The threaded end of the head is provided with longitudinally-tapered passages, into 80 which are fitted the tapered sleeves *v* *v'*, of mica or other suitable insulating material, the outer ends of these sleeves projecting beyond the threaded end of the head and the inner ends of the sleeves entering suitably-formed 85 recesses in the forwardly-projecting portion of the porcelain insulating-plate.

Into the open ends of the mica sleeves are driven tapered plugs *w* and *w'*, of brass or other suitable conducting material, which 90 hold the sleeves firmly in position. Into the ends of these plugs are fixed, respectively, the sparking electrodes *x* and *x'*, of platinum or other suitable material, the electrode *x'* consisting of a substantially straight piece of 95 wire and the electrode *x* of a similar piece, but bent or inclined toward the electrode *x'* herein with a substantially right-angled bend.

The plug *w* and its sleeve *v* are longer, respectively, than the plug *w'* and the sleeve *v'*, so that the sparking electrode *x* is protected by the insulation of the sleeve as far as the right-angled bend. Where terminal electrodes are used, a bridge of carbon deposit is 100 apt to be formed between the terminal points about where the insulation terminates. By carrying the insulation of one electrode be-

yond the other, however, and by abruptly turning the one terminal toward the other, the likelihood of bridging the electrodes from the described cause is greatly reduced.

5 The construction of the porcelain plate and the tapered mica sleeves provides highly-insulated passages or conduits for the secondary lead-wires y y' , which pass directly through the porcelain plate, the mica sleeves and the plugs w and w' , to which they are firmly secured by the tapered wedges driven in from the outer ends of the plugs.

10 The construction of plug described provides a compact but strong and durable and wholly waterproof casing for the coils and the lead-wires. The sparking electrodes are mounted upon the same structure with the secondary coil and directly connected thereto by heavily-insulated leads, thus avoiding the wasteful effect of a grounded secondary or lengthy secondary lead-wires, this feature in practice, as I have found, permitting the use of a coil of extremely small proportions, while obtaining a spark of the desired intensity.

15 I prefer to construct the casing f of some non-magnetic material, such as brass or composition, since I have found that the use of such material as an exterior casing greatly increases the efficiency of the coil and reduces the proportions of the secondary winding necessary to obtain a spark of sufficient size. To reduce the eddy-current loss which might arise in connection with the use 20 of a brass or other casing of relatively great conductivity, I preferably slit or cut away the walls of the casing at intervals lengthwise the coil, as represented at z .

25 The plug and coil described are adapted to be used with an exteriorly-arranged and independent vibrator and vibrator-magnet. Its construction permits the application of a number of these coils to the several cylinders of a multiple-cylinder engine while using a single exterior vibrator and vibrator-magnet, the coil-primaries being connected in multiple with each other and in series with a common circuit containing the battery and the vibrator-magnet. This arrangement associates the induction-coils in close proximity with the sparking terminals, avoiding the use of exposed secondary lead-wires, while having the practical advantage of a single vibrator for the several coils. The compact construction of combined spark-coil and plug permits its addition to the engine-cylinder, while occupying but little more room than the ordinary spark-plug.

30 While for illustrative purposes I have here shown and described one form of my invention, it is to be understood that the same is not limited to the details and form and arrangement of parts, but that these may be varied within wide limits without departing 35 from the spirit of the invention.

1 claim

1. A spark-plug carrying sparking electrodes and having a non-magnetic metallic casing containing an induction-coil, to the secondary of which said electrodes are connected, said casing having its walls cut away at separated intervals lengthwise the axis of the coil.

2. A spark-plug having insulated' sparking electrodes projecting from the inner end of the plug, the insulation of one electrode being carried beyond the insulation of the other.

3. A spark-plug having insulated' sparking electrodes, one of said electrodes being inclined or bent toward the other; the insulation of said electrode being carried approximately to the point of bend therein.

4. A spark-plug having a casing, a coil within said casing, insulated' sparking electrodes, to which the secondary winding of said coil is connected, an insulating-plate at the end of said coil having an outer raised recessed portion and insulating-sleeves entering the recesses in said raised portion through which the secondary lead-wires pass to the sparking electrodes.

5. A spark-plug having a casing, and a coil within said casing, said plug being provided with one or more apertures at one end thereof through which a coil lead-wire passes, and provided also with a tapered retaining-wedge driven into the said aperture to retain the lead-wire in position.

6. A spark-plug having a casing, an induction-coil in said casing, a head closing the end of said casing, an insulating-plate between said head and said coil, a pair of insulating-sleeves passing through said head and into said insulating-plate, a conducting-plug in the end of each sleeve, sparking electrodes secured to said plugs, and insulated conductors connecting the said plugs with the secondary of said coil and passing through said sleeves and insulating-plate.

7. A spark-plug having a casing; primary and secondary windings within the casing; a head having a threaded nipple closing one end of the casing; an insulating member within the casing between the windings and the said head and having openings through which the lead-wires from the secondary winding pass, a pair of insulating-sleeves passing through the said head and within the insulating member, said sleeves having each a tapered seat in the head, a tapered conducting-plug holding each of said sleeves to its seat, and sparking electrodes secured to the end of one of said plugs.

8. A spark-plug having a casing, primary and secondary windings therein, a head to which said casing is attached at one end, said head being provided with an attaching-nipple, insulation between said head and said windings, a pair of insulating-sleeves passing

through said head and extending from said threaded nipple, a conducting-plug in the end of each sleeve, sparking electrodes secured each to the end of one of said plugs, 5 and a pair of secondary lead-wires passing each from the secondary windings through the said insulation into the inner end of an insulating-sleeve and to the sparking electrode carried therein.

10. A spark-plug having a casing, an induction-coil in said casing, a head closing the end of said casing, a pair of insulating-sleeves passing through said head, sparking electrodes in the end of said head, and conductors connecting said electrodes with the secondary of said coil passing through said insulating-sleeves.

10. A spark-plug having a casing, a head provided with a threaded nipple closing the 20 end of said casing, a pair of insulated tapered sleeves passing through the nipple, said sleeves having each a tapered seat therein, a tapered conducting-plug driven into the inner end of each sleeve to hold the same to its 25 seat, a removable sparking electrode se-

cured to the end of each plug, and a conductor connected to each electrode and passing out of said sleeve at its opposite end.

11. A spark-plug having a casing, primary and secondary windings therein, a head to 30 which said casing is attached at one end, said head being provided with an attaching-nipple, insulation between said head and said windings, an insulating-sleeve passing through said head and extending from said 35 threaded nipple, a conducting-plug in the end of said sleeve, a sparking electrode secured to the end of said plug, and a secondary lead-wire passing from the secondary windings through the said insulation into the 40 inner end of said insulating-sleeve and to the sparking electrode carried therein.

In testimony whereof I have signed my name to this specification in the presence of two subscribing witnesses.

ISRAEL C. ORSWELL.
